UNITED STATES PATENT OFFICE

GEORGE HOWARD McNOLTY, OF SASKATOON, SASKATCHEWAN, CANADA, ASSIGNOR OF
ONE-HALF TO ARTHUR F. THOMAS, OF SASKATOON, CANADA

MOVABLE GRAIN DOOR JAMB

Application filed January 11, 1930. Serial No. 420,220.

My present invention has reference to railroad cars and the primary object of the invention is the provision of means whereby an ordinary box car may be converted into a grain car and further whereby the door sections of the car may be readily positioned or removed, and when so removed the car may be used as an ordinary freight car.

A further object of the invention is the provision of grooved jambs which are secured in the car and which receive the sections of the grain door therein, and wherein one of said jambs has a lower section which is movable from the exterior of the car, to align with the cooperating jamb section or movable away from such section to permit of the door engaged thereby being removed therefrom and likewise to permit of the door sections being arranged in the grooves of the jambs.

A still further object is the provision of a device for this purpose which can be readily attached to any ordinary construction of freight cars and which will not interfere with the ordinary sliding door for such cars, and further wherein the movable section of the improvement is effectively locked to hold the same in door engaging position and released and operated from the exterior of the car.

To the attainment of the foregoing broadly recited objects and many others which will present themselves as the nature of the invention is better understood, the improvement further resides in certain other novel features of construction, combination and operative association of parts, one satisfactory embodiment of which is disclosed by the accompanying drawings.

In the drawings:

Figure 1 is a longitudinal sectional view through an ordinary freight car illustrating the application of my improvement therein.

Figure 2 is a sectional view approximately on the line 2—2 of Figure 1.

Figure 3 is a sectional view approximately on the line 3—3 of Figure 1.

Figure 4 is a sectional view approximately on the line 4—4 of Figure 3.

Figure 5 is a perspective view of the removable jamb section.

Figure 6 is a similar view of the eccentrically mounted wheel or roller.

Figure 7 is a similar view of the shaft or 55 spindle for the wheel or roller.

In the drawings the numeral 1 designates a sufficient portion of an ordinary freight car to illustrate my improvement therein. In a line with the side walls that provide the opening for the ordinary slideable door 2 for the car 1 there is arranged upon the stiles or uprights 3 the jamb members that constitute my improvement. The jamb members are of metal and have their confronting faces grooved to receive the grain door sections 4 therein. One of the jamb members, indicated by the numeral 5, is fixedly secured throughout its length to one of the uprights 3, and the second jamb member comprises an upper section 6 which is removable but fixedly secured to the second upright 3 and a lower jamb section 7. The grooved or channeled face of the jamb section 7 is preferably formed on the end of a plate 8, but may be bolted to the said plate, as disclosed by the drawings. The plate 8 is preferably of a greater width than that of the jamb section 6, and the said plate is centrally formed with a reduced extension in the nature of what I will term a tongue 9. The tongue 9 is formed with a substantially rectangular opening 10. The tongue is guided for movement in a casing 11 which is suitably fixed to the inner side of the car, the outer face of the casing having its upper and lower edges flanged and these flanges abut with the inner plate 12 of the said casing. Suitable securing means 13 connect the plates 8 and 12 that constitute the casing. Between the plates 11 and 12 there are journaled rollers 14 with which the edges of the tongue 9 of the movable jamb section engage. Received in the opening 10 of the tongue 9 and contacting with the side walls thereof there is a wheel or roller 15. The wheel has an eccentric rod opening 16 and a notch 17 that communicates with the opening. The opening 16 is designed to receive therethrough the rounded portion 18 of a spindle 19 and the notch 17 is designed

to receive therein a lug 20 that is formed on the said part 18 of the spindle. The spindle is formed with a reduced extension 21 that is received in a suitable bearing opening in the outer plate 11 of the casing. The rounded portion of the stem extends through a bearing opening in the plate 12 of the casting and likewise through an opening in the side of the car 1. This portion of the spindle also is received through a bearing opening in a metal wear plate 22 which is fixed on the outer face of the side of the car. The spindle has an outer squared or hexagonal extension 23 that is received in a similarly shaped socket in the hub 24 of the operating wheel 25, there being suitable means 26 for holding the wheel on the said extension 23 of the spindle.

The wear or escutcheon plate 22 has 20 hingedly secured thereto, as at 27, a latch member 28. The body of this latch is rounded and has from its straight edge an opening 29 whose walls correspond with the shape of the spindle extension 23 and which notch 25 or opening is designed to receive the spindle therein when the latch is swung to latching position. The second or free end of the latch 28 is formed with a finger extension 30 that is designed to be received through an 30 opening in a keeper lug 31 that is integrally formed on the wear or escutcheon plate 22. The finger has an opening therethrough for the reception of a locking element 32 such as a cotter pin or the like.

35 The latch 28 will effectively hold the shaft or spindle 19 from turning and also hold the movable jamb section 7 in alinement with the upper and removably fixed jamb section 6.

When the latch is swung to released position and the hand wheel is turned the eccentric wheel or roller 15 contacting with the side walls of the opening 10 in the tongue 9, will impart a longitudinal movement to the jamb section 7 to bring the same, say away 40 from the fixed jamb section 6. This will permit of the door sections 4 being received in the grooves of the fixed jamb sections 5 and 6, and the lower door section 4 being arranged in the groove of the jamb section 5.

45 By turning the hand wheel in a second direction the jamb section 7 will be moved toward and in longitudinal alinement with the jamb section 6, so that the door 4 will be effectively held between the said movable section 5 and the removably fixed jamb 5. The latch is, of course, swung to latching position and is locked by the element 32 for holding the section 7 from movement. It is to be noted that while the improvement is arranged 55

60 upon the inside of an ordinary box car the operating means therefor is arranged upon the exterior of the car and further it will be noted that the improvement does not in any way interfere with the ordinary sliding door 65 2 for the said car. The grain door sections

4 may be constructed of either wood or metal and in the event that the sliding door 2 is not desired for its usual purpose the said door may be cut into sections and employed as a grain door.

70 The construction is extremely simple and the advantages thereof should appeal to those skilled in the art to which the invention relates. With my improvement it will be obvious that the breakage of grain doors commonly employed in connection with grain cars when nailed or otherwise crudely fixed thereon will be entirely obviated, that the improvement may be attached to any ordinary box or freight car constructions, that the improvement comprises few parts which may be cheaply constructed and easily assembled and erected and that the movable jamb section may be operated in an easy manner and with the least amount of physical exertion. 80

85 While I have herein set forth one satisfactory embodiment of the invention I desire it to be understood that I do not wish to be restricted to the details herein disclosed and, therefore, hold myself entitled to make such 90 changes therefrom as fairly fall within the scope of what I claim.

95 The fixed elements of the improvement are removably secured in the car to permit of the entry of the grain doors therebetween. 90

Having described the invention, I claim:

Jambs for the grain doors of cars, comprising members which have their inner faces grooved to receive the grain doors therein, one of said jambs comprising an upper removably fixed section and a lower movable section, said lower section having a tongue extension, a casing in which the said tongue is received, anti-friction bearings in the casing to engage with the edges of the tongue, said tongue having a rectangular opening therethrough, a roller received in the opening and contacting with the side walls thereof, a spindle journaled through the casing passing eccentrically through the roller and removably fixed to said roller, said spindle having a squared portion extending through the side of the car, an operating wheel having its hub fixed on the said portion of the spindle, an escutcheon plate on the outer side 100 of the car, provided with a bearing opening for the rounded portion of the spindle, a latch pivotally secured to the plate and having a central notched portion shaped to correspond with and to engage with the squared portion of the spindle, a finger extension on the free end of the latch, a keeper lug on the plate through which the finger passes and a removable locking element for the finger. 110
